(57) **CLAIM**

The ornamental design for a housing for a communication device and similar articles, substantially as shown.

DESCRIPTION

FIG. 1 is a perspective view of an ornamental design of a housing for radiotelephones and similar articles.

FIG. 2 is a first side view thereof.

FIG. 3 is a top plan view thereof.

FIG. 4 is a first end view thereof.

FIG. 5 is a second end view, opposite the first end view thereof.

FIG. 6 is a second side view, opposite the first side view thereof; and,

FIG. 7 is a bottom plan view thereof.

The broken line portions of the drawings are for illustrative purposes only and form no part of the claimed design.
